UNITED STATES PATENT OFFICE

2,284,354

BREATHER

Harry M. Acly, Pittsfield, Mass., assignor to General Electric Company, a corporation of New York

Application June 18, 1940, Serial No. 341,150

5 Claims. (Cl. 137—69)

The present invention relates to breathers and while it is not necessarily limited thereto, it is particularly applicable for use with liquid containing vessels such as oil filled transformer tanks.

In order to obtain high insulation levels for electrical apparatus such as a transformer, the assembled unit is thoroughly baked and dried so as substantially to remove all moisture therefrom. The unit arranged within a tank is then covered with an insulating oil having as one of its functions the prevention of absorption of moisture by the insulation. It is not always feasible to seal the vessel in a liquid tight manner and, in such instances, provision must be made to allow for expansion and contraction of the insulating liquid with variations in temperature of the apparatus under varying load conditions. A breather may be provided in an opening in the tank wall above the normal liquid level therein establishing communication between the space above the liquid level and atmosphere. The breathers commonly used heretofore were generally supplied as separate units to be attached to the transformers by the customer after the transformers were installed, since they permitted leakage of a considerable quantity of oil from the tanks during handling and shipment. To prevent the loss of oil from the tanks prior to the installation thereof, the tank vent openings were provided with special devices so designed as to minimize the splashing of oil therethrough. Such devices, however, included relatively small orifices and due to the high velocity of air passing therethrough, the abrupt changes of air temperature at the orifices would cause condensation of moisture from the air within the tank which moisture would contaminate the insulating liquid and be absorbed by the solid insulation. This might not be serious over a short period of time, but, as has been occasionally observed, customers after receiving a transformer so equipped may fail to replace the shipping attachment with the regular breather so that the transformer would be improperly and inadequately vented during the operation thereof.

It is therefore an object of the present invention to provide a new and improved breather for a liquid containing vessel which will substantially preclude the leakage of liquid therethrough during handling and shipment of the vessel and will provide adequate and moisture free ventilation for the vessel during the normal operation of enclosed apparatus.

For a better understanding of my invention,

attention is directed to the following description and the claims appended thereto taken in connection with the accompanying drawing, the single figure of which is a cross sectional view of a liquid containing vessel provided with a breather device constructed in accordance with the invention.

Referring to the drawing, 10 indicates a vessel or tank containing a liquid 11 such as insulating oil within which may be immersed an electrical apparatus such as transformer 12. The tank is provided with a cover 13 suitably clamped thereto as by bolts 14. The cover 13 is provided with an opening preferably adjacent one edge to which is secured a breather device of my invention generally indicated at 15.

The breather includes an outer cylindrical casing 16 which is closed at its upper and open at its lower ends and is suitably secured as by a weld 17 to the cover around the periphery of the opening. Concentrically arranged within the casing 16 is an inner casing 18 having an annular shoulder 19 between the upper portion and the enlarged lower portion, the outside diameter of which is substantially equal to the inside diameter of the casing 16. The inner casing 18 is open at its lower end while the upper end is provided with a plurality of relatively large radial vent openings 22. A disk cap 23 having a depending outer edge of a diameter somewhat greater than the outside diameter of the upper portion of the inner casing 18 is spaced between the upper end of the inner casing and the top of the outer casing by spacer blocks 24 and 25. The upper block 24 is suitably secured as by welding to the outer casing and is threaded for cooperatively receiving the end of the axially extending stem or bolt 26. Within the enlarged lower portion of the inner casing is a disk 27 having a relatively large central valve opening 28 therein, which disk is held against the under side of the shoulder 19 by means of a cylindrical spacer 29 arranged between the disk and a baffle plate 31. The baffle plate 31 is provided with a plurality of radially arranged openings 32 and is maintained in a spaced relation by washer 33 from the lower baffle plate 34 which is secured upon the lower end of bolt 26 as by nut 35. The outer edge of plate 34 is maintained in a spaced relation from the adjacent lower edges of the casings 16 and 18 by a plurality of spaced struckout portions 36. Slidably arranged upon the bolt 26 and within the space between the disk 27 and the baffle plate 31 is a float valve 38 the upper surface of which

in the elevated position thereof is adapted to engage with the periphery of the valve opening 28 to substantially close same and prevent the passage of liquid therethrough.

The outer casing 16 is provided with a vent opening 41 in the side wall thereof the lower edge of the vent opening being at least as low as the lowest portion of the space between the inner and outer casings. Suitably secured within the opening 41 is a length of pipe 42 extending substantially horizontally outwardly beyond the edge of the tank cover 13 and provided at the end with a downwardly extending elbow 43. Threaded into the downwardly facing open end of the elbow 43 is a screen disk 44 for preventing the entrance of insects or other foreign matter into the breather and tank.

The breather device as described is suitable for installation onto the tank at the factory. During the shipment of the apparatus and handling thereof incident to the installation of the transformer, the oil may be splashed around considerably within the tank without appreciable leakage. The force of the liquid waves striking against the breather opening will be materially reduced by the lower baffle plates 34 and 31. Any liquid, however, passing around the edge of the baffle plate 34 and upwardly through the openings 32 of disk 31 into the space thereabove will cause the float 38 to rise and close the opening 28 in the valve plate 21. Some liquid of course may escape through the valve opening 28 into the chamber thereabove within the inner casing 18 before the float 38 is moved to the fully closed position. Such liquid, however, is retained within the inner casing 18 until such time as the float 38 drops to its lower position when the liquid will be returned to the interior of the tank.

It will be observed that the disk cap 23 is spaced between the inner and outer casings so that its temperature will be nearer that of the air leaving the transformer than that of the outside atmosphere. Moisture will therefore not condense on its surface to the same extent as on the inside of the outer casing 16 as the outer surface of this part is in direct contact with the outside atmosphere. Any condensate which may collect on the inside walls of the outer casing 16 will be drained downwardly by the protective cap 23 extending over the openings 22 in the inner casing, into the space between the inner and outer casings and outwardly through the vent opening 41, pipe 42, and through the elbow 43 and screen 44. In order to prevent such moisture from seeping between the adjacent walls of the inner and outer casings at the adjacent lower portions thereof, it is preferred that they be brazed or soldered together in order to effect a fluid tight seal therebetween.

During the operation of the transformer, when it will ordinarily be stationarily mounted, the float 38 in its lowermost position will offer little if any restriction to the free passage of air between the interior of the tank and the outside. Since the various vent openings are all relatively large, the air passage through the breather device includes no flow restricting orifices likely to cause pressure differences on the opposite sides thereof and resultant formation of moisture.

Having described the principle of operation of my invention in what I now consider to represent a preferred embodiment thereof, I desire to have it understood that the specific details

shown are merely illustrative and that the invention may be carried out by other means.

What I claim as new and desire to secure by Letters Patent of the United States is:

- 5 1. A breather for a vessel containing a liquid and having an opening in an upper wall thereof above the normal liquid level therein, said breather comprising an outer casing secured to said wall about said opening, means arranged 10 in said outer casing defining a valve opening, a stem secured to said casing and extending axially through said valve opening, a float valve slidably arranged on said stem for closing said valve opening upon a predetermined abnormal 15 rise of liquid level in said vessel, an inner casing surrounding said valve opening and having vent passages in the upper portion thereof, and a vent opening in the lower portion of said outer casing.
- 20 2. A breather for a tank containing a liquid and having an opening in an upper wall above the normal liquid level therein, a casing secured to said wall around said opening, a plate extending across the interior of said casing and having a relatively large central valve opening therein, a stem secured to said casing and extending axially through said opening, a float valve slidably arranged on said stem beneath said valve opening, means spaced from the inner 25 walls of said casing defining a chamber above said valve opening and having a vent opening in the upper part thereof, and a vent opening in said casing.
- 30 3. A breather for application to an opening in a wall of a liquid containing tank, said breather comprising a casing to be secured around said opening and open at its bottom end, means defining a valve opening in said casing, a stem secured to said casing and extending axially through said opening, a float valve slidably arranged upon said stem beneath said opening, a vent opening in said casing on the outer side of said valve opening, said means having a vent opening in the upper portion thereof and spaced from said vent opening in said casing.
- 40 4. In combination a vessel containing a liquid, an opening in a wall of said vessel above the normal liquid level therein, a float movably arranged adjacent said opening for closing said opening upon the approach of the liquid level thereto, means defining a chamber around said opening on the outside of said wall for retaining liquid working past said float through said opening, vent openings in the upper portion of said means, a casing surrounding said means and having a vent opening in the lower portion thereof, and means arranged above said vent openings in the upper portion of said means and spaced from the inner surface of said casing.
- 45 50 5. A breather for a vessel containing a liquid and having an opening in an upper wall thereof above the normal liquid level therein, said breather comprising an outer casing and an inner casing sealed together at adjacent lower edges and adapted to be secured to said wall about said opening, said inner casing having a vent opening in the upper part thereof for communicating with the interior of said vessel through said wall opening, and a cap secured in a spaced relation between said casings and extending over said vent opening and a vent opening in said outer casing below said cap.
- 55 60 65 70

CERTIFICATE OF CORRECTION.

Patent No. 2,284,354.

May 26, 1942.

HARRY M. ACLY.

It is hereby certified that error appears in the printed specification of the above numbered patent requiring correction as follows: Page 2, second column, line 43, claim 3, after "opening," and before "said" insert --and means arranged between said valve opening and said vent opening for preventing liquid leaking past said valve from escaping through said vent opening,--; and that the said Letters Patent should be read with this correction therein that the same may conform to the record of the case in the Patent Office.

Signed and sealed this 28th day of July, A. D. 1942.

Henry Van Arsdale,
Acting Commissioner of Patents.
